(57) **CLAIM**

The ornamental design for a reticle for a telescopic gun scope, as shown and described.

DESCRIPTION

FIG. 1 is a front, top, left-side perspective view of the reticle for a telescopic gun scope according to a first embodiment; FIG. 2 is a front elevational view thereof, the rear elevational view being a mirror image of the front elevational view; FIG. 3 is a left-side elevational view thereof, the right-side elevational view being a mirror image of the left-side elevational view;

FIG. 4 is a top plan view thereof, the bottom plan view being a mirror image of the top plan view; and FIG. 5 is an enlarged front elevational view of area 5 shown in FIG. 2.

FIG. 6 is a front, top, left-side perspective view of the reticle for a telescopic gun scope according to a second embodiment; FIG. 7 is a front elevational view thereof, the rear elevational view being a mirror image of the front elevational view; FIG. 8 is a left-side elevational view thereof, the right-side elevational view being a mirror image of the left-side elevational view;

FIG. 9 is a top plan view thereof, the bottom plan view being a mirror image of the top plan view; and,

FIG. 10 is an enlarged front elevational view of area 10 shown in FIG. 7.
